UNITED STATES PATENT OFFICE

FRANK MARIANI, OF NEW YORK, N. Y., ASSIGNOR TO BEST DIE CASTING AND STAMPING COMPANY, INCORPORATED, OF NEW YORK, N. Y.

DESIGN FOR A HINGED MIRROR FOR AUTOMOBILE DOORS

Application filed August 13, 1930. Serial No. 36,652. Term of patent 7 years.

To all whom it may concern:

Be it known that I, FRANK MARIANI, a subject of the King of Italy, residing at New York city, State of New York, have invented a new, useful, original, and ornamental Design for Hinged Mirror for Automobile Doors, of which the following is a specification, reference being had to the accompanying drawings, forming part thereof.

I claim:

The ornamental design for a hinged mirror for automobile doors, as shown.

FRANK MARIANI.
